GRINDING MACHINE.

1,413,928.

Specification of Letters Patent. Patented Apr. 25, 1922.

Application filed November 7, 1919. Serial No. 336,341.

To all whom it may concern:

Be it known that we, ERVIN S. MUMMERT and JOSEPH O. DIXON, citizens of the United States, residing at Hanover, in the county of York and State of Pennsylvania, have invented a new and useful Grinding Machine, of which the following is a specification.

This invention has reference to grinding machines of the radial type and preferably, though not necessarily, of the portable type, and its object is to provide a grinding machine of such type which shall be easily portable and of great flexibility of operation and capable of performing heavy work under the control of a single operator.

In accordance with the invention, the machine is provided with a basic structure carrying a superstructure pivoted or swiveled to turn about an upright axis, and this superstructure in turn carries an elongated arm, at one end of which a grinding wheel is mounted, and at the other end of which there is provided a driving means for the grinding wheel connected to the latter, and which driving means may be a prime mover in the form of an electric motor. The arm and parts carried thereby, and mounted on the superstructure, are or may be initially balanced and provision is made for restoring the balance, should, for any reason, one end or the other of the arm be or become overbalanced. In order to adapt the grinding wheel to various work and to permit it to be moved so as to reach practically all parts of the work, and particularly to adapt the entire grinder to be brought into operative relation to heavy work, and moved about, the machine is or may be mounted on wheels so as to be moved in various directions after the manner of a truck. The superstructure, being movable about a vertical axis, permits the movement of the grinding wheel at the outer end of the long arm through arcs of various extents, or throughout a complete circle which may have a radial extent of a considerable number of feet. To vary the radial travel of the grinding wheel with relation to the basic portion of the structure, the arm is so mounted on the superstructure as to be moved thereon lengthwise of the arm for an appropriate distance without unbalancing the structure. In order to vary the

height of the grinding wheel from the floor or other support upon which the base rests, the arm has a horizontal axis about which it may be rocked, which axis may be much nearer the motor end of the arm than the grinding wheel end thereof, thus providing for an appropriate rise and fall of the grinding wheel. Furthermore, provision is made for twisting the grinding wheel about the longitudinal axis of the arm so that the point of attack of the grinding wheel may be varied angularly.

Each of the movements of the grinding wheel to different positions may be caused independently of the other movements, or in conjunction with one or more of them, whereby great flexibility is attained and the grinding wheel in its adjustments has practically a universal movement.

The invention will be best understood from a consideration of the following detailed description taken in connection with the accompanying drawings forming part of this specification, with the understanding, however, that the invention is not confined to any strict conformity with the showing in the drawings, but may be changed and modified so long as such changes and modifications mark no material departure from the salient features of the invention as expressed in the appended claims.

In the drawings,

Figure 1 is a side elevation of a grinding machine embodying the invention and showing a gear drive for the grinding wheel.

Figure 2 is a longitudinal vertical section through the machine of Figure 1, omitting certain parts and drawn on a larger scale than Figure 1.

Figure 3 is an end view of the grinding machine, with parts omitted and showing certain parts in cross section.

Figure 4 is a section on the line 4—4 of Figure 1, showing a portion of the superstructure and the basic part of the truck in elevation, the scale being the same as that of Figures 2 and 3.

Figure 5 is a side elevation of a somewhat different form of the working arm carrying the grinding wheel and motor therefor but omitting the supporting truck.

Figure 6 is a plan view of the structure

shown in Figure 5 and containing some parts not shown in Figure 5.

Figure 7 is an end elevation of the motor shelf shown in Figures 5 and 6.

5 Figure 8 is a section on the line 8—8 of Figure 6 but drawn on a larger scale.

Figure 9 is a longitudinal section, with some parts in elevation and drawn on a larger scale than the other figures, of the 10 grinding wheel end of the arm.

Figure 10 is a section on the line 10—10 of Figure 9.

Figure 11 is a section on the line 11—11 of Figure 10.

15 Figure 12 is an elevation of the left-hand end of the structure shown in Figure 9 with the handle omitted and showing the grinding-wheel hood in section.

Referring to the drawings, there is shown 20 a base 1 having a pedestal 2 rising therefrom, the base and pedestal being conveniently formed as a hollow casting, such structure providing ample strength without undue weight. The pedestal is mounted 25 upon pairs of supporting wheels 3 and 4, respectively, the wheels 3 being carried by fixed axles 5, and the wheels 4 being caster wheels carried by arms 6 projecting from the base 1. The wheel arrangement permits 30 the base to be moved about the floor or other support upon which the wheels rest, with all the flexibility of movement needed.

The top of the pedestal 2, which latter is a low pedestal, has a passage therethrough 35 defined by an inturned flange 7, and extending through this flange is a casing 8 provided at a point intermediate of its length with an exterior circumferential flange 9 secured by screws 10 to the inwardly directed flange 7, whereby the casing 8 is made fast to the top of the pedestal 2 and upstands therefrom, as well as projecting into the pedestal. Extending through the casing 8 is a hollow 40 neck 12 extending below the bottom of the casing and having a terminal head 13 above and overhanging the casing. At the lower end, the neck 12 has a ring 14 applied thereto and underriding the lower end of the casing. Between the upper and lower ends 45 of the casing and the head 13 at one end, and the ring 14 at the other end, are anti-friction bearings 15, 16, respectively, so that the head and neck may rotate freely in the casing, which, in turn, is made fast to the pedestal 2.

50 Fast to the head 13 is a frame 17, of generally rectangular form, comprising two substantially rectangular side members 18, 19, which may be of web and flange construction. The head 13 is provided with oppositely-extending arms 20, to which the sides 55 18 and 19 are secured by screws 21 or in other suitable manner, so that the side members 18, 19 are carried by the arms 20 fast to the head 13, and therefore swiveled by way 60 65 of the neck 12 in the pedestal 2. At the

upper end of a casing 8 are outstanding ears 22, and the head 13 has a similar outstanding ear 23 which may be brought into alignment with an ear 22, whereupon, by connecting the aligned ears by means of a pin 24, the 70 superstructure 17 may be locked to the pedestal so that the superstructure will no longer swivel on the pedestal.

The two side frames 18 and 19 are connected together at the upper ends by a cross bar 75 25 provided with a centrally located eye-bolt 26, by means of which the entire machine may be lifted by a crane or other suitable structure, either for transportation or repairs, or for any other suitable purpose. 80 The pin 24 is provided with an angle end 27 adapted to engage between two closely adjacent lugs 28, so that when it is not desired to have the pin 24 lock the superstructure and base of the machine together, the 85 pin may be lifted sufficiently to disengage the parts, and the angle end 27 then dropped between the lugs 28 to hold the pin elevated and out of engagement with the ear 22.

On opposite sides of each side frame 18 and 19 are arms or brackets 29, each with inwardly-directed ledges 30, those ledges on the respective frames 18 and 9 alining with each other. Carried by the ledges, which are located on the upper portions of the brackets 95 30, are rack bars 31, and closely adjacent to the rack bars are tracks 32, each track having upturned ends 33 with the racks bars 31 terminating closely adjacent to such upturned ends. 100

Extending longitudinally through the frame 17, midway of its width, is a tubular arm 34 having one end projecting far beyond the corresponding side of the frame 17, and the other end terminating within 105 the frame. At the shorter end of the arm 34 there is secured a shelf or bracket 35 in depending relation to the arm 34 and provided with an upstanding leg 36 traversed by said short end of the arm 34 and firmly 110 secured thereto. The shelf 35 is of suitable size and design to receive and support an electric motor 37, which may be assumed to be fed from a suitable source of current in the customary manner. The motor 37 is 115 provided with an armature shaft 38 connected by a coupling 39 to a drive shaft 40 extending through the hollow arm 34 and beyond that end of the latter remote from the coupling 39. 120

Gripping the arm 34 adjacent to the frame 17 is a clamp 41 with bolts 42, whereby the clamp may be tightened or loosened with respect to the arm 34. Secured to, or forming part of, the clamp 41 is an extension 43 thereof carried away from the frame 17 to one side of and parallel with the arm 34 and terminating in another clamp 44 embracing the arm 34 and capable of gripping the latter by means of a bolt 45. 130

Secured to the clamp 41, by screws 46 or otherwise, is a plate 47 carrying a housing 48 extended transversely of the length of the arm 34 and terminating at the ends in 5 roller bearing housings 49, 50. Extending through the axle housing 48 is an axle 51 carrying flanged wheels 52 at opposite ends in position to engage the track 32 and roll thereon. Secured to the wheels 52 are gear 10 wheels 53 at opposite ends of the axle 51 and positioned to mesh with the racks 31. The wheels 52, engaging the tracks 32, support the arm 34 and the parts carried thereby, so that the arm 34 may be moved lengthwise 15 through the frame 17 for a limited distance determined by the upturned stop ends 33 of the tracks. The gear wheels 53, engaging the racks 31, maintain the arm 34 strictly in the line of travel and prevent any side 20 sway or movement thereof, since the gear wheels, being fast to the shaft, must turn in unison, and meshing with the racks, must maintain the proper relation to the remainder of the machine, thereby compelling the 25 arm 34, when moved lengthwise, to travel in a straight line. By loosening the clamps 41 and 44, the arm 34 may be adjusted lengthwise so that a balance is established between the end carrying the motor 37 and 30 the other end of the arm. When the arm 34 is appropriately balanced pendently from the axle 51 as a substantially horizontal axis, the arm may be very easily rocked, whereby the end of the arm remote from the 35 motor 37 may be raised or lowered with but little effort, the resistance to the rocking movement being reduced to a minimum by suitable roller or other anti-friction bearings located within the housings 49 and 50. 40 Such roller bearings are not shown, since they may be of any known type suitable for the purpose.

The rocking movement of the arm 34 about the axis of the shaft 51, as well as the 45 longitudinal movement of the carriage, may be controlled by a set screw or pin 54 carried by an arm 55 projecting from the housing 49 and in position to engage in a hole in the adjacent wheel 52, thus locking the arm 34 50 in a horizontal position when it is desired to carry the grinder about, the said arm serving the same purpose as a vehicle tongue in shifting the machine from place to place. When the screw or pin 54 is released, the 55 arm and its carriage may be moved in either direction through the frame 17, since then the axle 51 is free to turn to permit the wheels 52 to travel along the tracks 31 between the stops 33, the arm 34 being then 60 maintained in a straight path by the connected gear wheels 53, and, if it be so desired, the arm 34 may then be rocked as needed about the axis of the axle 51.

At the end of the arm 34, which, in Figure 1 and associated figures, is indicated as a

hollow rod, there is secured an elongated head 56 shown in detail in Figures 9, 10, 11 and 12. The head 56 is split longitudinally and is secured to the corresponding end of the arm 34, which enters the head for an appropriate distance, by bolts 57. The arm 34 has a reduced continuation 58, best shown in Figure 10, entering a neck 59 extending from a block 60. The neck 59 is provided about midway of its length, or at other appropriate point, with an exterior annular flange 61, in which there is provided a circular series of radial sockets or passages 62, any one of which is adapted to be entered by a locking pin 63 extending through a boss 64 deformed on the head 56. The pin 63 is designed to secure the block 60 to the head 56 and to permit turning of the block 60 and parts carried thereby about the longitudinal axis of the arm 34, when desired.

The shaft 40 is continued through the arm 34, where carrying the head 56, and also through the block 60, where the shaft 40 has keyed to it a bevel pinion 65, antifriction bearings 66 being interposed between the 90 pinion 65 and an adjacent wall of the block 60 to serve as thrust bearings. Fast to the block 60 is a casing 67 which need not be described in detail, since it serves simply the function of a housing for an arbor 68 mounted in antifriction bearings 69, 70, the arbor carrying a bevel pinion 71 within the casing and in mesh with the pinion 65. The arbor 68 is carried through the corresponding end of the casing and turns about an 100 axis at right angles to the axis of the shaft 40. Beyond the end of the casing through which the arbor projects, said arbor has fast to it a grinding wheel 72 held in place by the usual clamp plate 73 and nut 74. Fast to the casing 67 is a guard 75 on the operator's side of the grinding wheel 72, which latter may be an emery wheel or any other suitable type of grinding or abrading wheel or other rotatable tool capable of use on the 110 machine. The casing 67 has an attaching bracket 76 and lug 77, to which is secured a grip or hand-hold 78, whereby an operator may grasp that portion of the machine carrying the grinding wheel 72 to direct it 115 against the work to be treated.

In order to reinforce the arm 34, which may be several feet in length, there is provided a brace member 79 in the form of a tube with one end screwed into a lug or boss 120 80 on the corresponding end of the head 56, and the other end extended through the extremity 36 of the shelf 35, where the brace or rod 79 has applied to it a holding member 81 indicated in Figures 1 and 2 as a pipe 125 elbow, although not necessarily confined to such fitting. The elbow 81 serves as a holding means for the brace 79 and also as a mouth or entrance to the brace 79, which, being in the form of a pipe, is utilized as a 130

conduit for electric conductors 82 connected to the motor 37. The brace 79 includes a switch carrier 83 mounted on the arm 34 and secured thereto by a set screw 84 or in other suitable manner. The carrier 83 is designed to hold an electric switch 85, which may be of the familiar snap type or of other form and is located close to the grinding end of the arm 34 so as to be within convenient reach of an operator grasping the handle 78.

The hollow brace rod or bar 79 is arranged above the arm 34 so that the weight of the grinding end of the arm and the parts forming such end, while tending to bend the arm, is resisted tensionally by the rod or brace 79, whereby the action of the rod 79 is similar to that of a truss. In order to hold the rod 79 in substantially parallel relation to the arm 34 and thereby enhance the stiffening effect, the space between the rod and arm may be traversed, where needed, by bolts 86 between the ends of which and the rod and arm, clips 87 are interposed, this being shown in Figure 1.

In the structure shown in Figure 1 and associated figures, the power transmission from the motor to the tool, represented by the grinding wheel 72, is by way of shafts and gearing. In the structures shown in Figures 5, 6, 7 and 8, a belt drive is employed between the motor and the tool. The differences between the two forms of power transmission constitute the principal differences between the machines as a whole, wherefore those parts of the machine which are not directly concerned with the type of power transmission, are not illustrated in Figures 5 to 8.

In the belt drive, an arm 34^a is provided, carrying at one end a bracket 35^a having an extremity 36^a made fast to the corresponding end of the arm 34^a. At the other end of the arm 34^a is a swivel head 56^a held in set positions by a pin 63^a, and held on the arm 34^a by collars 88 at opposite ends of the head 56^a. In depending relation to the head 56^a is a flange or bracket 89 with an offset portion 90 carrying suitable journal bearings for an arbor 91 for the grinding wheel 72, and also carrying the hood or guard 75 for the grinding wheel. The head 56^a also carries a handle 78^a which may be quite similar to the handle 78 and shown in Figures 1 and 9.

Since, in the structure of Figure 1 and associated figures, the motor 37 has its armature shaft 38 alined with the drive shaft 40, the arm 34 and bracket 35 may be centralized with relation to the machine as a whole. In the belt drive form of the machine, there is provided an electric motor 37^a with a pulley 92 at the end thereof, and this motor 37^a is mounted crosswise of the machine, wherefore the bracket 35^a is properly constructed for such purpose. The sup-

porting leg 36^a of the bracket 35^a is located at one side thereof, while another similar supporting leg 36^b receives a short rod or tube 93 carried by a clamp member 94 made fast to an axle housing 48^a, like the axle housing 48 of the structure of Figure 1 and associated figures. Extending through the housing 48^a is an axle 51^a like the axle 51, and rising from a clamp 41^a, fast to the axle housing and gripping the arm 34^a, is an arm or post 95 with a cradle 96 at its upper end. Engaging a bracket 97 rising from the clamp 36^a is a hollow rod or tube 79^a extending over the cradle 96 to a switch carrier 83^a made fast to the arm 34^a near the grinder end of the arm. The tube or hollow rod 79^a constitutes a truss brace for the arm 34^a, and a conduit for conductors 82^a for the motor 37^a, the same as in Figure 1 and associated figures.

In Figure 1, the brace 79 is secured to the switch carrier 83, and, similarly, the brace 79^a, Figure 5 and associated figures, is connected to the switch carrier 83^a.

The arbor 91 in the structure of Figure 5 and associated figures, carries a belt pulley 98 between which and the pulley 92 there extends a belt 99.

Besides the handles 78 and 78^a, the heads 56 and 56^a are each provided with another handle 100 projecting from the heads on the side thereof remote from the grinding tool 72. This permits firm control of the grinding tool by a single operator.

In the structure of Figure 5 and associated figures, the axle 51 carries track-engaging wheels 52 and gear wheels 53, the same as in the structure of Figure 1 and associated figures, and the purpose and operation thereof is the same. For this reason, it is deemed unnecessary to describe these parts separately.

In setting up the machine, or at any time when the machine is liable to be out of balance, the clamps holding the arm 34 or 34^a are loosened sufficiently to permit longitudinal shifting until the motor end and the grinding end of the arm 34 or 34^a are balanced, or very nearly so. Now, the machine may be moved by an operator grasping the handle 78 or 78^a to any point desired, where the work is to be encountered, the truck-support of the machine facilitating such movements, and the swivel of the superstructure on the truck permitting even a relatively heavy machine to be moved with ease from place to place about the shop. When the machine has been suitably located, the exposed grinding edge of the grinding wheel is brought into engagement with the part to be treated by lifting or lowering the grinding end of the arm 34 or 34^a and by turning the head carrying the grinding tool about an axis longitudinally of the arm so much as may be needed. The grinding tool

70

80

85

90

95

100

105

110

115

120

125

130

is capable of a relatively large movement without moving the truck at all since the arm 34 or 34^a may be swung about the upright axis of movement of the superstructure 5 on the truck toward any point of the compass, and moreover the effective length of the arm 34 or 34^a with respect to the superstructure carrying it may be varied throughout the limits of the length of the 10 tracks between the stops 33. The bodily movement, the circular movement, the rocking movement, the in and out movement and the twist of the grinding head about the longitudinal axis of the supporting arm 15 provides universal movement of the grinding head and the positioning of the latter at any point throughout a wide area and throughout a considerable height, whereby the grinding tool may be made to act upon 20 nearly all parts of the work without bodily movement of the supporting structure of the tool, and such bodily movement may be brought about with little effort, due to the easy running qualities of the structure, even 25 when of considerable weight.

The arm 34 or 34^a, as the case may be, is utilizable as a tongue, whereby the operator may draw the machine about the shop, and in such instance, the superstructure and 30 pedestal are locked together by the pin 24 and the pin 54.

What is claimed is:—

1. A grinding machine comprising a hollow base, and a superstructure with 35 grinding mechanism thereon swiveled to the base to turn about an upright axis, the swivel connection comprising a head forming the lower portion of the superstructure and provided with a depending neck entering within the base, a casing carried by and 40 fast to the base and extending above the base and also depending within the same and traversed by the neck, a ring mounted on the lower end of the neck and under- 45 riding the lower end of the casing, and anti-friction bearings between the head and casing and supporting said head and super-structure, and also between the ring and casing to prevent lateral play of the neck 50 in the casing.

2. A grinding machine comprising a supporting truck having wheels swiveled thereto, a superstructure swiveled to the truck to turn about an upright axis, means 55 for temporarily locking the superstructure and truck together, an arm extending through the superstructure with one end terminating close to the superstructure on one side thereof and the other end project- 60 ing beyond the superstructure on the other side thereof, an electric motor carried by the short end of the arm, an axle carrying the arm adjacent to the motor end thereof, means for temporarily locking the axle 65 from turning movement, a grinding tool

carried by the long end of the arm, driving connections between the motor and grinding tool, and a manipulating handle for the grinding end of the arm, whereby when said temporary locking means are made 70 active the long end of the arm may be utilized as a tongue for drawing and directing the machine from place to place.

3. A grinding machine provided with a basic portion and a superstructure, tracks 75 on opposite sides of the superstructure, rack bars adjacent to the tracks, an arm extending through the superstructure and beyond one end thereof, an electric motor carried by one end of the arm, a tool carried by the 80 other end of the arm, driving connections between the motor and tool, an axle carrying the arm adjacent to the motor end thereof, wheels on the ends of the axle engaging the tracks and supporting the arm 85 from the tracks, and gear wheels fast to the axle and engaging the rack bars.

4. A grinding machine provided with a basic portion and a superstructure, tracks 90 on opposite sides of the superstructure, rack bars adjacent to the tracks and substantially parallel with the same, an arm extending through the superstructure and beyond one end thereof, an electric motor carried by one end of the arm, a grinding 95 tool carried by the other end of the arm, driving connections between the motor and tool, an axle carrying the arm adjacent to the motor end thereof, wheels on the ends of the axle engaging the tracks and supporting the arm from the tracks, and gear wheels fast to the axle and engaging the 100 rack bars, the tracks having stop means at the ends to limit the travel of the wheels along the tracks.

5. A grinding machine provided with an elongated arm with an electric motor at one end, a grinding tool at the other end, and driving connections between the motor and tool, tracks adjacent to and on opposite 110 sides of the motor end of the arm, rack bars adjacent to the tracks, an axle carrying said arm, wheels on the axle engaging the tracks to support the said arm from the tracks, and gear wheels on the axle and engaging 115 the rack bars to permit the longitudinal movement of the arm along the tracks.

6. In a grinding machine, an elongated arm having an electric motor at one end, a grinding tool at the other end, supporting means for the arm on opposite sides thereof along which the arm is longitudinally movable, and means coacting with the supporting means for constraining the arm in its travel along the supporting 120 means to a straight line, said last-named means comprising rack bars on opposite sides of the arm, and connected rotatable gear wheels engaging the rack bars, with the axis of rotation in fixed relation to 125 130

the arm, whereby the engagement of the gear wheels and rack bars constrains the arm to move lengthwise without side movement.

5 7. A grinding machine comprising a supporting structure, an arm mounted on the supporting structure to rock about a horizontal axis, and also having a longitudinal movement, driving means at one end of the 10 arm, a grinding tool at the other end of the arm, connections between the driving means and the tool, and means located at said axis for temporarily locking the arm against both longitudinal and rocking movements.

15 8. A grinding machine comprising a supporting structure and an arm mounted on the supporting structure for rocking movements about a substantially horizontal axis, 20 the mounting for the arm comprising an axle, wheels on the axle, tracks for the wheels, gear wheels on the axle, and rack bars associated with the tracks for engagement by the gear wheels.

25 9. A grinding machine comprising a supporting structure and an arm mounted on the supporting structure for rocking movements about a substantially horizontal axis, the mounting for the arm comprising an 30 axle on which the arm is pivoted, wheels on the axle, tracks for the wheels, gear wheels on the axle, rack bars associated with the tracks for engagement by the gear wheels, and means for locking the arm against rocking movements about the axle.

35 10. A grinding machine comprising a supporting structure, and an arm mounted on the supporting structure for rocking movements about a substantially horizontal axis, 40 the mounting for the arm comprising an axle, on which the arm is pivoted, wheels on the axle, tracks for the wheels, gear wheels on the axle, rack bars associated with the tracks for engagement by the gear 45 wheels, and a short arm projecting from the first-mentioned arm adjacent its pivotal connection with said axle, said short arm carrying locking means to engage with one of said wheels to lock said first-mentioned arm 50 against rocking movements about the axle.

55 11. A grinding machine comprising a supporting structure, an elongated arm, power means at one end of and carried by the arm, a grinding tool at the other end of the arm, 60 driving connections between the power means and grinding tool, a pivotal support for the arm, and means whereby the arm may be adjusted in the direction of its length with respect to the pivotal supporting means and held in adjusted position to balance the 65 arm and parts carried thereby.

65 12. A grinding machine comprising an elongated arm, a supporting structure therefor, a pivotal support for the arm carried by 70 said structure, a motor, a bracket for sup-

porting the motor, said bracket being connected to one end of the arm at one side of its pivotal support, a grinding tool at the other end of said arm, driving connections between the motor and grinding tool, and 75 clamping means for gripping said arm at the other side of the pivotal support, whereby the arm may be adjusted in the direction of its length to balance the arm and parts carried thereby and then locked in its adjusted position. 75

13. A grinding machine comprising an elongated arm, a supporting structure therefor, a pair of connected clamps engaging the arm at spaced points, a housing carried by 80 one of the clamps, an axle passed through the housing and constituting the pivotal axis of said arm, wheels mounted on the axle, tracks for said wheels carried by the supporting structure, a motor supported at 85 one end of the arm at one side of said axis, a grinding tool at the other end of said arm, the said clamps gripping the arm at that side of the pivotal axis remote from the motor, whereby the arm may be adjusted 90 longitudinally to balance the arm and the parts carried thereby and then locked in its adjusted position.

14. A grinding machine comprising an elongated rock arm with a power unit at 95 one end, a grinding tool at the other end, driving connections between the power unit and grinding tool, and means associated with the axis of rocking of the arm for permitting lengthwise movements of the arm and 100 locking the arm in adjusted positions of longitudinal adjustments whereby to balance the arm and permit rocking movements thereof.

15. In a grinding machine, a supporting 105 structure, an elongated arm mounted on the supporting structure and having a long end projecting therefrom, an electric motor on one end of the arm, a grinding tool on the other end of the arm, driving connections 110 between the electric motor and the grinding tool, an electric switch on the arm adjacent to the end thereof remote from the motor, and a hollow truss or tie-rod arranged above and connected to the arm and constituting both a brace for the arm and a conduit for electric conductors extending from the switch to the motor. 115

16. In a grinding machine, a supporting 120 structure, an elongated tubular arm mounted on said structure, an electric motor on one end of said arm at one side of said structure, a grinding tool on the other end of said arm, a shaft passed through said arm, means connecting said shaft to said motor, gearing between said shaft and the grinding tool, a hollow rod arranged above and connected at each end to the tubular arm, that end of the rod adjacent the motor having a mouth for the insertion of electric conductors from the 125 130

motor into and through said rod, and an electric switch carried by said rod at the end remote from said motor.

17. In a grinding machine, a supporting structure, an elongated arm, a pivot support for the arm mounted on the supporting structure and on which pivot support the arm is rockable about a horizontal axis, an electric motor carried by one end of the arm, a grinding tool carried by the other end of the arm, driving connections between the motor and tool, an electric switch adjacent to the end of the arm carrying the grinding tool, a post erected on the pivotal connections, and a hollow rod connected at the ends to the end portions of the arm and extending over and seated on the post and constituting a truss or tie-rod for the arm and a conduit for electric conductors extending from the switch to the motor.

18. A grinding machine comprising a truck, a superstructure mounted on the truck to move therewith, an elongated arm mounted on the super-structure to turn about a horizontal axis, a motor supported on one end of said arm at one side of said axis, a grinding tool mounted on the other end of said arm, driving connections between said

motor and said tool, and locking means located at said axis for temporarily holding said arm against rocking movements, whereby the rock arm is held fast to the super-structure and said arm may be used as a tongue for drawing and directing the machine from place to place.

19. A grinding machine comprising a supporting structure, an elongated arm pivotally mounted on said structure, a power member on one end of the arm, a grinding tool at the other end of the arm, driving connections between the power member and the tool, and means whereby the arm may be adjusted lengthwise of the supporting structure without disturbing the pivotal connection and made fast to the structure in the adjusted position to establish a balanced condition of the arm.

In testimony that we claim the foregoing as our own, we have hereto affixed our signatures in the presence of two witnesses.

ERVIN S. MUMMERT.
JOSEPH O. DIXON.
